UNITED STATES PATENT OFFICE.

WILLIAM H. FOSTER, OF NEW YORK, N. Y., ASSIGNOR OF ONE-HALF TO WILLIAM O. TAYLOR, OF NORTH PLAINFIELD, NEW JERSEY.

DRIFTING-VALVE MECHANISM FOR LOCOMOTIVE-ENGINES.

1,077,695.

Specification of Letters Patent.

Patented Nov. 4, 1913.

Application filed July 3, 1913. Serial No. 777,225.

To all whom it may concern:

Be it known that I, WILLIAM H. FOSTER, of the borough of Bronx, in the city, county, and State of New York, have invented a certain new and useful Improvement in Drifting-Valve Mechanism for Locomotive-Engines, of which improvement the following is a specification.

My invention relates to valve mechanism for controlling the admission of a small quantity of steam to the cylinders, or to the valve chest, of a locomotive engine, when drifting, or running with the throttle closed, for the purpose of maintaining sufficient lubrication and preventing the formation of a vacuum in the cylinders; the object of the invention being to provide an improved valve mechanism of simple construction, which may be readily applied, and which shall be governed by the movement of the locomotive to automatically and positively close such admission when the locomotive comes to a stop or when the speed is reduced below a certain low rate, and to automatically open and permit a limited quantity of steam to flow to the cylinders when the locomotive is running at or above said predetermined minimum rate of speed.

The improvement claimed is hereinafter fully set forth.

In the accompanying drawings: Figure 1 is a plan or top view of a portion of a locomotive frame and cylinders, showing one form of my improvement in horizontal section; Fig. 2, a central section of my improved governor and valve, upon a larger scale; Fig. 3, a side elevation of one form of driving means for the governor, the locomotive axle being shown in transverse section; and Fig. 4, a transverse section of the governor shaft showing the sliding collar.

According to the construction shown in the drawings, my invention is exemplified in connection with a balanced valve, 1, of the piston type, having heads, 1^a, 1^b, and 1^c, with intermediate annular cavities, 1^d, and 1^e, said valve operating in a casing, 2, having an inlet port communicating with a pipe, 3, leading from the boiler or source of live steam supply, and an outlet port communicating with pipe, 4, leading to the valve chest, 6, and cylinders, 7, of the locomotive. The stem, 5, of the valve passes loosely through an opening in one end of the cas-

ing, and the other end is provided with a leakage port, 2^a, so that any steam leaking by the piston valve heads, which carry suitable packing rings, readily escapes to the atmosphere, and the opposite heads of the valve are subject to atmospheric pressure. In this way the valve is balanced at all times and offers little or no resistance to movement within its casing.

The valve casing is preferably mounted on the locomotive frame, 8, and when the valve is in its normal closed position, that is with the locomotive at rest or moving but very slowly, communication from inlet pipe, 3, to outlet pipe, 4, is cut off, but when the locomotive is running at a speed above the predetermined minimum, the valve moves to its open position, in which the cavity, 1^a, establishes communication from pipe, 3, to pipe, 4, and a limited quantity of live steam is permitted to flow to the engine cylinders, as determined by the capacity of the small ports or passages.

For the purpose of operating the valve in accordance with my invention, any means governed by the movement of the locomotive, which will automatically open the valve when running above a certain speed, and close the same when the speed is reduced below a predetermined minimum, or when the locomotive is at rest, may be employed. A preferred construction comprises a centrifugal governor such as shown in the drawings, and which may be mounted on a fixed shaft, 9, bolted by means of a bracket, 10, to the frame, 8. Rotatably mounted upon said shaft is the grooved pulley, 11, having rigid arms, 12, to which are pivoted the centrifugal weights, 13, coupled by links, 14, with the rotatable collar or sleeve, 15, on the shaft, 9. Another collar, 16, is slidably mounted on the shaft in contact with the sleeve, 15, but is prevented from rotating by a key and keyway connection with the shaft. A spring, 17, acting against a nut, 18, at the end of the shaft, 9, holds the collar, 16, in contact with its sleeve, 15, and opposes the outward movement of the centrifugal weights, 13, suitable connections, such as rods, 19, and plate, 20, being made with the stem, 5, of the piston valve for actuating the same by the centrifugal movement of the weights. The rotatable head of the pulley, 11, is mounted between a shoulder on the

shaft, and a fixed collar, 21, and for the purpose of limiting the outward movement of the centrifugal weights in the open position of the valve, stop lugs, 22, and 23, may 5 be provided on the arms, 12, and the weights, 13, respectively.

Any suitable driving connection may be employed for the rotatable head, 11, such 10 for instance as a belt, 24, which may be formed of coiled wire and driven from a grooved split pulley, 25, mounted on an axle, 26, of the locomotive.

When the locomotive is running with the 15 throttle open, the governor is being rotated at such speed that the weights are thrown outward against the limiting stops by the centrifugal force, thereby moving the collars, 15 and 16, longitudinally upon the shaft, compressing the spring, 17, and actuating the balanced piston valve to its open 20 position, in which the inlet pipe, 3, communicates, through the cavity, 1^d, with the outlet pipe, 4, thereby admitting a limited quantity of steam through said pipes to the 25 engine valve chest and cylinders. The admission of this very small additional quantity of steam to the engine cylinders at the time that the throttle is open, is, of course, immaterial, and has no appreciable effect, as 30 the amount of steam thus admitted is inconsequential compared to that admitted through the throttle valve. When, however, the throttle is closed and the locomotive continues running, or "drifting" as it is called, 35 the movement of the pistons in the engine cylinders tends to create a vacuum therein, and at such times the small quantity of steam admitted to the engine cylinder by means of my improvement is sufficient to 40 prevent the formation of a vacuum, and the carbonization of the oil, and maintain an efficient lubrication in the cylinder.

When the locomotive comes to a stop, or 45 when the speed is reduced below a predetermined minimum, such as from one half to one mile per hour, as determined by the adjustment of the spring, 17, this spring then overcomes the centrifugal force of the 50 weights, moving the same inward, and the valve, 1, to its closed position, in which communication is cut off between the pipes, 3, and 4, which then communicate with the respective cavities, 1^d and 1^e, in the valve. In 55 this way the supply of the small quantity of steam through the balanced valve is automatically and positively cut off when the lo-

comotive comes to rest or when the speed is reduced below a certain minimum rate.

The supply pipe, 3, may be connected, at any convenient point, to the live steam space 60 of the boiler.

I claim as my invention and desire to secure by Letters Patent:

1. A drifting valve mechanism for locomotive engines, comprising a valve for controlling the admission of a limited amount of steam to the engine cylinders, and means operated by the movement of the locomotive for governing said valve. 65

2. A drifting valve mechanism for locomotive engines, comprising a valve for controlling the admission of a limited amount of steam to the engine cylinders, and a speed governor operated by the movement of the locomotive for actuating said valve. 70

75 3. A drifting valve mechanism for locomotive engines, comprising a valve for controlling the admission of a limited amount of steam to the engine cylinders, and a centrifugal governor driven from an axle of the locomotive for opening and closing said valve.

80 4. A drifting valve mechanism for locomotive engines, comprising a valve for controlling the admission of a limited amount of steam to the engine cylinders, and means driven by the running of the locomotive for opening said valve and adapted to close the same when the speed is reduced below a certain minimum rate. 85

90 5. In a drifting valve mechanism for locomotive engines, the combination of a balanced valve for controlling the admission of a limited amount of steam to the engine cylinders, and a centrifugal governor driven by the movement of the locomotive for opening said valve and adjusted to close the same upon a reduction of speed below a certain minimum rate.

100 6. In a drifting valve mechanism for locomotive engines, the combination of a balanced piston valve having its opposite heads subject to atmospheric pressure, and controlling the admission of a limited amount of steam to the locomotive cylinders, and a speed governor device driven by the movement of the locomotive for operating said valve. 105
